UNITED STATES PATENT OFFICE.

JULIUS WEIS, OF ST. PAUL, MINNESOTA.

EGG-CRATE.

No. 894,924.

Specification of Letters Patent. Patented Aug. 4, 1908.

Application filed March 4, 1907. Serial No. 360,439.

To all whom it may concern:

Be it known that I, JULIUS WEIS, a citizen of the United States, residing at St. Paul, in the county of Ramsey and State of Minnesota, have invented a new and useful Improvement in Egg-Crates, of which the following is a specification.

My invention relates to improvements in egg crates and more particularly to that class which is provided with stalls to be occupied by individual articles to be carried, such as eggs, fruit, glass bottles, etc.

The primary object of my invention is to provide what I have chosen to term a "co-filler" which is strong and durable combined with low cost of production and using as small an amount of material as is possible.

I have found in the practice of my invention that it is essential that all materials be made up in such shape so as to be light in weight and so that the co-filler can be packed in as small a space as possible to save space in storage and shipping, and also to obtain the lowest freight rates. I accomplish these results by the means as pointed out in the following specification and claims.

In a general way, my invention consists of a co-filler made of paper board or sheets of any suitable material and formed with indentations and reinforcements, such filler being adapted to be placed at the lower and upper ends of a series of collapsible stalls or compartments to support them in a suitable enclosure when the latter is upright or inverted. These fillers can be made direct from different kinds of pulp used for making paper or straw board, pulp board, paper, veneered wood, metal, composition, or any other thin, durable and flexible material.

In the accompanying drawings, forming part of this specification, Figure 1 is a side view of my invention partly broken away and with one side of the egg case removed; Fig. 2 is a plan view of my invention partly broken away and with the cover of the case removed; Fig. 3 is a perspective view of the co-filler; Fig. 4 is a detail end view, enlarged, of the co-filler.

In the drawings A represents an egg crate made of any suitable construction, that shown being provided with a cover 2. In this crate are nested a series of compartment fillers B having horizontal partition floors 3 all of ordinary construction. At the upper and lower ends of the series of compartment fillers are what I have chosen to term co-

fillers C which serve the purpose of cushioning the contents of the partition fillers when the case is upright or inverted. The co-filler which involve the new features of my invention are of similar construction.

Each co-filler consists of a sheet of suitable material rolled, pressed or otherwise formed with a series of longitudinal indentations D which are joined by intervening webs E between them, and transverse reinforcements F across said sheet.

As shown in Figs. 1 and 2 the reinforcements F are placed at each end of the sheet while in Fig. 3 a third transverse reinforcement 4 is provided between the ends of the sheet and across said indentations, the latter being arranged in two parallel rows 5. The indentations are substantially V-shaped, the sides 6 and 7 and ends 8 being slightly curved at 9 where they join the sheet and connect together. The shapes of the indentations with the curved joints as described permit a number of co-fillers to be packed snugly together with substantially no intervening waste 80 spaces. When the co-fillers are made by rolling, pressing or stamping, the reinforcements are slightly crimped and then flattened as illustrated in Fig. 4 in order to take up the excess material when the indentations are 85 reinforced.

As illustrated in Figs. 1 and 2 the indentations are placed below the walls of the compartment filler and the webs below the compartments, the latter forming cushions for 90 the eggs or other articles in the compartments to rest upon.

The fillers are perforated at 10 so that the thumb or fingers of the hand can be inserted for the purpose of lifting or unpacking them 95 from a case. These perforations are preferably arranged in different positions so as to be staggered as related to each other when they are packed for storage or shipping. The edges of the sheets of the co-fillers adjoining 100 the sides of the indentations are cut away at 11 and provided with a tongue 12 so as to reduce the amount of material necessary for constructing them.

In accordance with the patent statutes, I 105 have described the principle of operation of my invention, together with the apparatus which I now consider to represent the best embodiment thereof, but I desire to have it understood that the apparatus shown is only 110 illustrative and that the invention can be carried out by other means within the scope

of the following claims and applied to uses other than those above set forth.

Having described my invention, what I claim as new and desire to protect by Letters Patent, is:—

- 5 1. A device of the class set forth, comprising, in combination with a suitable inclosure, a compartment filler in said inclosure, and a single - piece co - filler across said compartment filler consisting of a sheet having cushioning supporting indents, intervening webs, and transverse reinforcements across said indents to support said webs.
- 10 2. A device of the class set forth, comprising, in combination with a suitable inclosure, a compartment filler in said inclosure, and a single-piece cushioning co-filler across said compartment filler, comprising a sheet having a series of substantially parallel supporting indents and a transverse reinforcement across said supporting indents, for the purposes specified.
- 15 3. A device of the class set forth, comprising, in combination with a suitable inclosure, a compartment filler in said inclosure, and a single - piece cushioning co - filler co-acting with said compartment filler to form individual stalls, said co-filler having a sheet formed with a series of substantially V-
- 20 30 shaped supporting indents with intervening webs between them, and transverse re-

inforcements across the ends of said webs, for the purposes specified.

4. A device of the class set forth, comprising, in combination with a suitable inclosure, 35 a set of compartment fillers in said inclosure, and single-piece cushioning co-fillers across the ends of said series of compartment fillers, comprising sheets having supporting indents, webs between the supporting indents of each 40 sheet, and reinforcements across the ends of said supporting indents.

5. A device of the class set forth, comprising, in combination with a suitable inclosure, a compartment filler in said inclosure and a 45 single-piece cushioning co-filler across said compartment filler, consisting of a sheet having supporting indents below the spaces in said compartment filler, webs between said supporting indents and below the ends 50 of the walls of said compartment filler, and reinforcements across said supporting indents strengthening said indents under a load.

In testimony whereof, I have signed my 55 name to this specification, in the presence of two subscribing witnesses.

JULIUS WEIS.
